COMBINATION WEATHER STRIP

Filed June 12, 1929

INVENTOR.
John J. Behen
Francis H. Davis

ATTORNEY:

UNITED STATES PATENT OFFICE

JOHN J. BEHEN, OF SOLEDAD, CALIFORNIA

COMBINATION WEATHER STRIP

Application filed June 12, 1929. Serial No. 370,835.

My invention relates to weather-strips and particularly to that type adapted to seal the space beneath a door so as to exclude weather and dust, and if desired the threshold may be dispensed with; it further relates to a door-stop adapted to hold the door at any position of the opening arc; and furthermore, relates to an alarm bell which automatically gives warning when the door is opened.

5 The objects of the invention comprise the following desideratum:—

To provide a vertically-operable weather-strip member carried by a door between the bottom thereof and a floor or threshold said 15 strip being provided with rubber or other suitable yielding lower surface adapted to make close contact with a floor.

To provide bifurcated cranks forking a push-shaft to impart even up and down movement to a weather-strip; to provide dual means for axial displacement of said shaft, one means being automatic with the opening or closing of the door, the other operated by pressure of the foot upon either of two pedals, 25 one being disposed at each side near the swinging lower corner of the door.

To provide a bell that will sound an alarm whenever the weather strip is raised or lowered.

30 With the foregoing and other advantages, the invention consists in the novel construction, arrangement and combination of parts, particularly defined in the claims and illustrated in the accompanying drawings, in 35 which:—

Figure 1 is a longitudinal sectional elevation of my invention taken on the line 1—1 of Fig. 2.

40 Fig. 2 is a section taken on the line 2—2 of Fig. 1.

Fig. 3 is a section taken on the line 3—3 of Fig. 2.

Fig. 4 is a section taken about on the line 45 4—4 of Fig. 3.

Fig. 5 is an enlarged elevational view of a stop pedal.

Fig. 6 is a general projectional view of the lower portion of a hinged door and relative components of my invention.

Fig. 7 shows another form of my door-stop element.

Fig. 8 is an elevational view of my regulatory abutment.

Fig. 9 is a sectional elevational view taken 55 on the line 9—9 of Fig. 8.

Similar numerals refer to similar parts throughout the several views.

In the drawings, the numeral 2 designates a door of a preferred form of construction and 3 a frame. By reference to Figs. 2 and 4 it is seen that the bottom of the door is provided with the medial groove 4 milled up vertically for the full width thereof. Said groove being of sufficient width to receive the frame of the device as is well shown in Figs. 1, 2, 3 and 4. Said frame comprises the upper structure 5 with the ends 6 and 7 respectively. Said structure being a snug fit up into said groove; but the respective end plates 6 and 7 are preferably of sufficient width for the screws 8 to secure the structure 5 to the door structure at each side of said groove, as is clearly indicated by the dotted lines 6—6 in Fig. 2, the door structure being 60 gained out to receive said plates.

The main bearings 9, 10 and 11, as well as the plate 7 are suitably drilled to carry the main shaft 12 in axial alinement with the groove 4 and in a horizontal plane.

Said shaft being adapted for pre-determined axial displacement.

The cam-plate 13 is rigidly secured to the shaft 12 by a pin as 14 or in other suitable manner.

85 The adjacent face of said plate and the bearing 9 contact with the relative sides of the stop cranks 15 or 15^a as the case may be.

In my preferred construction as shown in Fig. 1 the pivotal axis 16 of the crank 15 is disposed beneath the shaft 12 whereas, in a second embodiment, shown in Fig. 7, the crank 15^a is pivoted above said shaft 12.

90 Said pivot 16 is preferably of square section and passes transversely through the door and through a square opening in either of said cranks 15 or 15^a with enough end projecting at each side of the door to mount the socketed flanges 36 and 36^a. The hubs 35^a—35^a of the pedal elements fit into the 95 100

sockets 35^b—35^b and center the pivotal shaft 16, being held in place by the means 35^e—35^e the projections 35 are stops to limit the pedal-throw in either direction beyond the required throw of the crank 15 or 15^a.

To secure the crank 15 from falling to the horizontal when the door is closed, which traverses the plate 13 to the left, I provide a retaining spring which may be as 37^a in Figs. 2 and 3 or as 37^a the preferred form shown in Fig. 4 wherein the ends of the spring 37^a are secured to the respective flanges 36 and 36^a with the bight 37^b of the spring passing round in to the front of the crank 15 so as to tighten when the crank is moved to the horizontal, thus constituting a yieldable check to prevent said crank falling down and thus locking the device when the plate 13 is remote, a situation which might occur when the door is shut.

To the right of the bearing 9 the compression spring 16^b is slipped on the shaft 12, the double-faced cam-block 17 is rigidly secured to said shaft so as to compress said spring 25 to a considerable degree and so as to present said cam-faces in vertical planes adapted for inter-engagement with the bifurcated crank 18 whose lower limb 19 extends suitably to the left to make slotted inter-engagement 30 with the pin 20 connecting said limb with the member 21 which carries the left end of the weather-strip element 22, the axis 23 of the crank 18 being carried transversely in the bearing member 24 depending vertically 35 from the structure 5 and preferably integral therewith. Passing to the right said shaft 12 is carried by the bearing 10 and 11. The spring 16^c is under moderate compression between the bearing 11 and the cam-block 17^a, 40 the interengaging crank 18^a being a duplicate of the crank 18 previously described, it is pivoted in the bearing member 24^a by the axis 23^a, the lower limb 19^a of said crank making slotted inter-engagement by means 45 of the pin 20^a with the member 21^a which carries the right end of said weather-strip element.

The right-hand portion of the shaft passes through a suitable perforation in the plate 50 7 and has sufficient end 25 projecting to cause suitable axial displacement of the shaft 12 by contacting with the abutment member 26 when the door 2 is shut, as will be further explained.

55 The abutment element comprises the shell 27 and the abutment member 26 which screws tightly thereinto well shown in Fig. 9, the head 28 fitting into the counterpart recess 29, said head being preferably concaved on its outer surface 33 and provided with the screw-driver slots 30. Said abutment element is fitted into the frame 3 so as to be in alinement with the center of the shaft 12 when the door 2 is shut, the flange 32 being let in flush with the frame and is secured thereto

by the screws 31, in which relation the concavity 33 can be regulated axially of the recess 29 by counter clockwise movement of the head 28.

The manipulation and action of my novel invention are as follows:—

Assuming that the device is installed as described; then, with the door ajar as in Fig. 6 the weather-strip element is well up within the groove 4. If it is desired to hold the door stationary in any opened position the corresponding limb 34 or 36^b must be depressed until contacting with the stop 35 thus moving either said crank from a vertical to a horizontal position where it remains so locked either by the energy exerted by the springs 16^b and 16^c now compressed or by traversing beyond the center of the axis 16 to the stop element 35, this described action of said crank moves the shaft 12 to the left, thus depressing limbs 19 and 19^a of their related cranks, thereby bringing the weather-strip element 22 down hard against the floor, causing the element to act as a perfect door-stop, not merely by pressing against a point against the floor, as is the case with other door-stop devices but by applying a stop member to the floor surface which extends for the full width of the door. In this position the door will remain until pressure, as of the foot, is applied to the releasing limb 34 or 36 as the case may be, whereupon the springs 16^b and 16^c, now released, force the shaft 12 back to the right to its normal position.

When the door is closed the end 25 of shaft 12 abuts into the concavity 33 and the strip element simultaneously descends and presses on the floor or threshold as the case may be; for floors of various levels from the bottom of the door regulative adjustment of the throw of the cranks 19 and 19^a may be had by manipulation of the abutment member 26 by screwing it out of the shell 27 said abutment being adjusted to govern the most extreme floor levels when seated in said shell as shown in Fig. 9.

As a means to prevent the crank 15 falling to the left when the door is closed and the plate 13 thereby removed to the left, the spring 37^a is provided having sufficient resistance to maintain said crank in upright position until acted upon by axial displacement of the shaft 12.

The spring 37^a is of a changed form from the spring 37^d, the ends whereof are secured respectively to the members 36 and 36^a with the bight 37^b passing behind the crank 15 under suitable compression to hold said crank from falling involuntarily, yet being sufficiently yieldable to permit the proper throw thereof.

In a second embodiment the crank 15^a normally hangs downward until turned up slightly above center as shown in Fig. 7, by

downward movement of the limb 36^b, thus traversing the shaft 12 to the left.

The bell, B is preferably applied as shown somewhat diagrammatically in Fig. 6, this feature is old and needs no further description as a bell, sufficient to say that it will ring when the member 37 is moved horizontally, said member is connected with the cam block 17^a by means of the shaft 38 working in the elongated slot 38^a so that when the door is opened the extension of the springs 16^b and 16^c will rasp the member 37 past a means to sound the bell, the bell being sounded by means actuating a weather-strip.

It is believed that the construction, operation and advantages of the invention will now be clearly understood. The present embodiments of the invention have been disclosed in detail merely by way of example, since in actual practice they attain the features of advantages set forth as desideratum in the statement of the invention and the above description.

Numerous changes in the details of construction, and in the combination and arrangement of parts may be resorted to without departing from the spirit or scope of the invention as hereinafter claimed or sacrificing any of its advantages.

Having thus described my invention, what I claim as new is:—

1. A weather-strip structure comprising a structural metallic frame mounted in a longitudinal groove in the bottom of a door, a rod mounted in the frame for regulated axial displacement, a cam plate secured to the left end of said frame a vertically-disposed crank mounted in said frame in contact with said plate and a bearing, means on both sides of the door to actuate said crank, a spring means under partial compression between said bearing and a cam-block rigidly secured to the rod, said crank being adapted to traverse said rod to the left, said spring being adapted to draw the rod back to normal when the crank is turned back to vertical; said cam block having vertical parallel sides forming grooves for inter-engagement with a bifurcated angle crank whose upper ends fork the shaft from below, the angle of said crank being pivoted to the frame, the lower limb of said crank making slotted engagement with means connecting the left hand end of a weather-strip member thereto, the under surface of said member being composed of yieldable matter adapted to make a perfect closure beneath the door, the elements adjacent the right-hand end of the device comprise a bearing, a similar spring to the former under partial compression between said bearing and a cam-block being a similar cam-block to the former, a bell-shaft projecting therefrom in a horizontal plane, a bifurcated crank similar to the former engaging said cam-block and said weather-strip, said bar projecting out-

wardly from said frame to contact with an abutment element carried by a door-post; said parts and elements constituting means, whereby when the door shuts, or when the foot crank is operated the resilient strip will descend and make perfect closure beneath the door.

2. In a weather-strip device as set forth in claim 1, a transverse pivotal shaft adapted to actuate said vertically-disposed crank, socketed bearing members on each side said door, surrounding the ends of said shaft, pedal elements journaled in said sockets and adapted to actuate said shaft

3. In a weather-strip device as set forth in claim 1, a transverse pivotal shaft adapted to actuate said vertically-disposed crank, socketed bearing members on each side said door, surrounding the ends of said shaft, pedal elements journaled in said sockets and adapted to actuate said shaft and stop elements adapted to limit rotation of said shaft in either direction.

4. In a weather-strip device as set forth in claim 1, a transverse pivotal shaft adapted to actuate said vertically-disposed crank, socketed bearing members on each side said door, surrounding the ends of said shaft, pedal elements journaled in said sockets and adapted to actuate said shaft and stop elements adapted to limit rotation of said shaft in either direction said stop elements carried by said socket bearings.

5. In a weather-strip device as set forth in claim 1, a transverse pivotal shaft adapted to actuate said vertically-disposed crank, socketed bearing members on each side said door surrounding the ends of said shaft pedal elements journaled in said sockets and adapted to actuate said shaft and spring means for yieldably holding said crank in vertical position.

6. In a weather-strip device as specified in claim 1, and in combination with said axially displaceable rod means connecting said rod with a bell so that longitudinal movement of the rod will automatically ring the bell.

7. In a weather-strip device as defined in claim 1, a regulatively-adjustable abutment element adapted to coact with the projecting end of said rod, said element comprising a fixed shell member adapted to be sunk into a doorpost, an abutment member adapted for relative adjustive movement within said shell to or from the projecting end of said rod, said adjustive movement constituting regulative closure means for doors of different levels above the floor.

In testimony whereof I have signed my name to this specification, this 27th day of May, 1929.

JOHN J. BEHEN.
